CONVERTIBLE CHAIR

James J. Duffy and Jacob Corngold,
Los Angeles, Calif.

Application August 29, 1950, Serial No. 182,062

7 Claims. (Cl. 155—40)

1

This invention relates to a convertible chair and more particularly to a child's chair which may be converted to meet varying conditions as the child increases in growth.

The primary object of the invention is to enable a chair to be employed as a highchair such as is used by infants, and subsequently to be converted into a youth's chair, or into a rocking chair, according to the desires of the user.

Another object is to rigidly hold the various parts in the desired positions until such time as changing of the relative position of the parts is desired.

The above and other objects may be attained by employing this invention which embodies among its features a pair of vertically disposed spaced side members, a seat carried by the side members and extending horizontally, therebetween, a pair of spaced vertical leg members, pivotally connected to the side members adjacent the lower ends thereof and substantially midway between the forward and rear ends of the seat, cross bars carried by the leg members and extending transversely therebetween, and, latches carried by the seat for engaging said cross bars and releasably holding the leg members against rotation about their respective pivots.

Other features include interconnected latch members carried by the seat and means for moving said latch members into released position simultaneously.

Still other features include a foot board adjustably and detachably connected to the seat.

In the drawings:

Figure 1 is a plan view of a convertible chair embodying the features of this invention;

Figure 2 is a side view of the chair illustrated in Figure 1 showing it converted into a rocking chair;

Figure 3 is an enlarged fragmentary sectional view taken substantially along the line 3—3 of Figure 2;

Figure 4 is an enlarged horizontal sectional view taken substantially along the line 4—4 of Figure 2;

Figure 5 is an enlarged fragmentary view partly in section illustrating the manner in which the foot board is adjustably connected to the seat member;

Figure 6 is an enlarged view of the latches;

Figure 7 is a fragmentary sectional view on an enlarged scale taken substantially along the line 7—7 of Figure 6; and

Figure 8 is a side view of the chair showing it converted into a youth's chair, and illustrating in dotted lines the position of the parts when the chair is employed as a highchair.

2

Referring to the drawings in detail this improved chair comprises spaced vertically extending leg members designated generally 10 and 12 and each such leg member comprises a curved base 14 which in certain positions forms rockers when the chair is converted into a rocking chair. Extending upwardly from each curved member 14 from the concave side thereof is a bar 16 which is provided at its end remote from the curved member 14 with a return bend 18 having an extension 20 which extends toward the curved base bar 14 and diverges relative to the bar 16 as it recedes from the return bend 18. The extension 20 is fixed to the curved bar 14 intermediate the junction of the bar 16 with the bar 14 and an end of the bar 14. Fixed to each bar 14 substantially midway between the junctions of the bars 16 and 20 therewith is an inwardly extending plate 22 which is provided intermediate its ends with an opening 24 for the reception of a pivot pin 26 by means of which an adjacent side member to be more fully hereinafter described is pivotally coupled to a leg member 10 or 12. The structure just described forms a substantially hollow triangle having curved members and are held in spaced vertical relation to one another by cross bars 28, 29 and 30. The cross bar 28 is connected at opposite ends to the respective leg members 10 and 12 between the junctions of the bars 14 and 20 and the adjacent ends of the rocker bars 14 while the cross bar 29 is connected at opposite ends to the bars 14 between their junctions with the bars 16 and the opposite ends of said rocker bars 14. The cross bar 30 is connected at opposite ends to the bars 16 substantially midway between their junctions with the bars 14 and the return bends 18. By thus employing the cross bars 28, 29 and 30, the leg members 10 and 12 are held in spaced vertical relation and form a substantial base frame for the device.

Pivots supported on each pivot pin 26 is a tubular sleeve 32 which extends through and is rigidly fixed in a return bend 34 of each side member 36 and 38. Each such side member comprises the return bend 34 carrying divergent legs 40 and 42. Each leg 40 and 42 terminates at its upper end in an angular extension 44 and 46. These extensions when the parts are assembled extend across the leg members to support the seat to be more fully hereinafter described between said leg members. Arm rests 48 are carried at the inner ends of the angular extensions 44 and 46 in spaced parallel relation to the side members 36 and 38.

Suspended from the arm rests 48 is a seat structure designated generally 50 which comprises a seat frame covered with a fabric 52. The seat

frame above referred to comprises a pair of depending bars 54 which are secured at their upper ends to the arm rests 48 and carry at their lower ends inwardly extending opposed horizontal bars 56 which project toward one another between the side members 36 and 38 and terminate at their adjacent ends in spaced parallel members 58 which lie substantially parallel to the arm rests 48. The ends of the members 58 remote from the bars 56 terminate in divergent extensions 60 which extend outwardly toward the extensions 46 of the side frames 36 and 38 and hence project upwardly to form a support for fabric 62 which forms the back of the chair. As illustrated in Figure 1, the members 58 lie in substantially closely spaced parallel relation to form a support for the latch members to be more fully hereinafter described.

Supported on the members 58 is a plate 64 (see Figure 6), of substantially elongated rectangular formation, and carried by the plate adjacent opposite ends thereof are depending ears 66 which are pierced with aligning apertures for the reception of pivot pins 68 and 70. Mounted for rocking motion on the pivot pin 68 is a latch member 72, and a similar latch member 74 is mounted for rocking movement on the pivot 70. The latch member 72 is provided adjacent one end with a notch 76 for the reception of either cross bar 28 or 30 of the leg members 10 and 12, while the opposite latch member 74 is provided with a notch 78 for the reception of the cross bar 29 of the leg members 10 and 12. Formed on the latch member 72 at the end thereof remote from the notch 76 is a longitudinally projecting tongue 80 which underlies a longitudinally projecting tongue 82 carried by the latch member 74 at the end thereof remote from the notch 78. It will thus be seen that when the latch member 74 is moved about its pivot 70 in a counterclockwise direction, the tongue 82 thereof will engage the tongue 80, and cause the latch member 72 to move about its pivot 68 in a clockwise direction. A bowed spring 84 lies between the plate 64 and the latch member 72 in order to yieldingly hold the latch members 72 and 74 downwardly. A knob 86 is carried by the latch member 74 adjacent the end thereof remote from the tongue 82 so that the latch member 74 may be lifted upwardly into released position against the effort of the spring 84 when it is desired to change the position of the leg members 10 and 12 relative to the seat 50.

A foot rest designated generally 87 may be detachably connected to the chair and comprises a platform 88 supported on a bar 90 which has lateral extensions 92 at opposite ends thereof. Formed on the ends of the extensions 92 remote from the bar 90 are upwardly extending legs 94 which carry at their upper ends a yoke 96 which is substantially U-shaped and is provided with legs 98 and 100 respectively which are adapted to engage opposite sides of the depending bars 54 when the foot rest 87 is employed. As illustrated in Figures 4 and 5, the depending bars 54 are provided with vertically spaced openings 102, and carried by the leg 100 at the end thereof remote from the yoke 96 is an upwardly extending arm 104 having a horizontally extending arcuate portion 106 which partially embraces its respective depending bar 54 and carries a lug 108 for entrance into one of the openings 102 in order to lock the foot rest 87 against vertical movement relative to the seat 50.

In use it will be understood that when the chair is to be used as a highchair, the leg mem-

bers 10 and 12 are rotated about the axes of the pivots 26 so that they assume the dotted line position illustrated in Figure 8 in which case the cross bar 28 is engaged in the notch 76 of the latch member 72. In this way the parts are locked against relative movement and with the foot rest 87 mounted on the seat suspension bars 54, the device may be used as a highchair. When it is desired to employ the chair as a youth's chair, the foot rest 87 is removed, and the latches 72 and 74 moved to released position so that the cross bar 28 is freed to permit the leg members 10 and 12 to move about the axes of the pivots 26 into the full line position illustrated in Figure 8 at which time the cross bar 29 will be engaged in the notch 78 of the latch 74. With the parts in this position, the chair seat will be lower and the device may be employed as a youth's chair. In order to convert the device into a rocking chair, the latches are released to permit the bar 29 to be removed from the notch 78 and the leg members are swung about the axes of the pivots 26 into the position illustrated in Figure 2, at which time the cross bar 30 is engaged in the notch 76 of the latch 72. In this position, the curved bases 14 of the leg members 10 and 12 will be disposed downwardly and serve as rockers for the chair.

While in the foregoing there has been shown and described the preferred form of this invention, it is to be understood that minor changes in the details of construction, combination and arrangement of parts may be resorted to without departing from the spirit and scope of the invention as claimed.

We claim:

1. In a convertible chair, a pair of spaced vertical side members, an inwardly offset substantially horizontal arm rest carried by each side member at the upper end thereof, a seat structure carried by said arm rests and suspended therebetween, a pair of spaced vertical leg members positioned between said side members, a pivot coupling between each side member adjacent the lower end thereof and the adjacent leg member, said pivot couplings lying in a vertical plane passing through the seat structure substantially midway between the forward and rear ends of the seat, cross bars connected to the leg members and extending transversely therebetween, and latches carried by the seat structure engaging one of said cross bars and releasably holding the leg members against rotation about said pivot couplings.

2. In a convertible chair, a pair of spaced vertical substantially triangular side members, an inwardly offset substantially horizontal arm rest carried by each side member adjacent the upper end thereof, a seat structure carried by the arm rests and suspended therebetween, the major portion of the seat structure being below the level of said arm rests, a pair of spaced vertical substantially triangular legs connected to the side members adjacent the lower convergent ends thereof whereby a rocking movement, which traces the swing of vertical arcs, which lie between the seat and side members, is followed by the ends of said legs, cross bars connected to the legs and extending transversely therebetween, and latches carried by the seat structure engaging one of the cross bars and releasably holding the legs against movement between the seat structure and the arm rests.

3. In a convertible chair, a pair of spaced vertical side members, an inwardly offset substantially horizontal arm rest carried by each side

member at the upper end thereof, a seat structure carried by said arm rests and suspended therebetween, a pair of spaced vertical substantially triangular leg members positioned between said side members, a horizontal pivot coupling between each side member adjacent the lower end thereof and the adjacent leg member, said pivot coupling lying in a vertical plane passing substantially midway between the forward and rear ends of the seat, one side of each leg member being convexly curved to form a rocker, cross bars connecting the leg members and extending transversely therebetween, and latches carried by the seat structure engaging one of the cross bars and releasably holding the legs against rotation about their pivots.

4. In a convertible chair, a pair of spaced vertical substantially triangular shaped side members having their apices disposed downwardly, a seat structure suspended from the upper ends of the side members in spaced relation thereto, said seat structure being suspended between the side members, a pair of spaced vertical substantially triangular shaped leg members pivotally connected adjacent their bases to the side members adjacent the apices of the latter, cross bars connected to the leg members and extending transversely therebetween, and latches carried by the seat structure and in selective engagement with one of said cross bars to releasably hold said leg members against rotation about their pivots.

5. In a convertible chair, a pair of spaced vertical substantially triangular shaped side members having their apices disposed downwardly, a seat structure suspended from the upper ends of the side members in spaced relation thereto, said seat structure being suspended between the side members, a pair of spaced vertical substantially triangular shaped leg members, each leg member having a convex base to form a rocker thereon, means connecting the side members adjacent the apices thereof to the legs adjacent the convex bases thereof for movement in spaced vertical arcuate paths between the side members and the seat structure, cross bars connected to the leg members and extending transversely therebetween, and latches carried by the seat structure and in selective engagement with one of said cross bars for holding the leg members

against movement in the vertical arcuate paths.

6. In a convertible chair, a pair of spaced vertical substantially triangular shaped side members having their apices disposed downwardly, a seat structure suspended from the upper ends of the side members in spaced relation thereto, said seat structure being suspended between the side members, a pair of spaced vertical substantially triangular shaped leg members, each leg member having a convex base to form a rocker thereon, pivots connecting the side members adjacent the apices thereof to the legs adjacent the convex bases and intermediate opposite ends thereof, a cross bar connected to the legs adjacent the convex bases thereof and extending transversely between said legs, a second cross bar connected to the legs in spaced relation to the first mentioned cross bar and extending transversely between said legs, and latches carried by the seat structure and extending parallel with the legs in engaging one or the other of said cross bars and releasably holding the legs against rotation about their respective pivots.

7. In a convertible chair, a pair of spaced vertical side members, an inwardly offset substantially horizontal arm rest carried by each side member at the upper end thereof, a seat structure carried by said arm rests and suspended therebetween, a pair of spaced vertical leg members pivotally connected to the side members adjacent the lower ends thereof and substantially midway between the forward and rear ends of the seat structure, cross bars carried by the leg members and extending transversely therebetween, and oppositely extending simultaneously releasable latches carried by the seat structure in selective engagement with one of said cross bars to releasably hold the leg members against rotation about their respective pivots.

JAMES J. DUFFY.
JACOB CORNGOLD.
